UNITED STATES PATENT OFFICE.

LUCIUS D. COPELAND, OF LOS ANGELES, CALIFORNIA.

STEAM BOILER.

Application filed July 5, 1923. Serial No. 649,430.

This invention relates to steam boilers and particularly to boilers which are adapted for use in steam automobiles.

The general object of the invention is to provide a steam boiler or generator, which is highly efficient, and which will be effective for a long period of time.

One of the specific objects of the invention is to provide a steam boiler of the drop water tube type wherein parts of the boiler may be removed to allow them to be cleaned.

A further object of the invention is to provide a removable circulation tube for steam boilers.

15 An additional object of the invention is to provide a boiler of the drop tube type with means for increasing the heating area in contact with the products of combustion.

Another object of the invention is to provide a novel form of spring for holding the circulation tube of a steam boiler in position.

An additional object of the invention is to provide a drop water tube boiler having a holding tube united to the drop tube in such a manner that the two tubes can be removed as a unit.

Further objects of the invention will be apparent from the following description taken in connection with the accompanying drawings wherein Fig. 1 is a perspective view of a boiler embodying the features of my invention; Fig. 2 is a sectional view, partly in elevation, showing the boiler tubes and flues; Fig. 3 is a section on line 3-3, Fig. 2; and Fig. 4 is a section on line 4-4, Fig. 2.

Referring to the drawing by reference characters, I have shown a boiler embodying the features of my invention at 10. This 40 boiler is indicated as comprising a shell 11 having top and bottom portions 15 and 14. The boiler is also provided with an inlet 16 and with an outlet 17.

The boiler shown is preferably of the drop tube type and as indicated, the shell 11 is provided with a plurality of depending water tubes 20. Each of the water tubes 20 is shown as provided at its upper end with a holding tube 21. This holding tube is preferably brazed as at 22 to the drop water tube 20 or the parts may be united in any other desired manner.

It will be noted that the holding tube 21 extends entirely through the shell 11 and that the closure 14 of the shell 11 is beveled to match a corresponding bevel on the top

of the tube 20. The two beveled surfaces, which may be ground, afford a steam tight joint. The upper end of the holding tube 21 is preferably threaded as at 23 and this 60 threaded portion is engaged by a cap 25. This cap is preferably provided with a lower beveled surface 26 which may coat with the similar surface on the closure portion 15.

From the foregoing description, it will 65 be apparent that the drop water tubes 20 may be easily removed from the boiler by loosening the holding nut 25 and withdrawing the tube 20 from the boiler casing.

In order to provide for proper circulation of water through the drop water tube, I show a circulation tube 30. This circulation tube comprises a hollow member which extends to a point adjacent the bottom 31 of the tube 20 and is provided with one or 75 more apertures 32 adjacent the lower end. The upper portion of tube 30 is shown as provided with a flange 33 which is disposed adjacent the inner wall of the tube 21.

The holding tube 21 is shown as provided 80 with a plurality of apertures, the top apertures being indicated at 35, the intermediate apertures at 36, and the lower apertures at 37. The apertures 35 and 36 serve to furnish means whereby the water may enter the circulation tube 30 whence it passes downward in this tube and out through the apertures 32. Water passing from the aperture 32 is at once heated as it comes in contact with the tube 20 and this water rises in the space 90 between the tube 30 and the inner wall of the tube 20, and passes out of the apertures 37 in the tube 21.

The circulation tube 30 is loosely positioned within the drop water tube 20 and in order to maintain it in proper position I may provide a spring 40 here shown as a leaf spring having a lower curved portion 41 for engaging the end of the circulation tube. The other end of the spring 40 is preferably 100 engaged by the cap 25.

From the foregoing description it will be apparent that the drop water tube 20 and the holding tube 21 constitute in effect a single 105 unitary member and that they may be removed, repaired, and replaced while in this unitary condition.

I have shown in Fig. 1 at 50 a heating element for raising the temperature of the water in the boiler. This heating element 110 50 which may be an oil burner is intended to be merely illustrative of any one of a number

of heating elements which can be used with my invention.

In drop water tube boilers it is essential to provide means for increasing the area of the water tubes in contact with the fire. I am aware that previous to my present invention fins have been used upon the exterior surface of the drop water tube in order to increase the heating area. These fins have proven objectionable, however, in that they require considerable room and, moreover, the distance of the front edge of the fin from the tube is such that the desired conduction of heat is not secured.

15 To overcome the difficulty just mentioned, I provide a plurality of fire tubes 55. These tubes which may vary in number, as desired, are illustrated in Fig. 4, as arranged upon the surface of the tube 20. The flues or 20 tubes 55 are preferably united to the drop water tube 20 by brazing as at 56. This operation causes a considerable amount of metal to be disposed between the joined pipes and this relatively large amount of 25 metal aids in conducting the heat from the tubes 55 to the central tube 20. It is a well known fact that metal is a good conductor of heat and it will be readily apparent that the gases passing about the fire tubes 55 and 30 within these tubes will raise the temperature of the metal of which the tube is composed and this heat conducted through the tubes 55 to the tube 20 raises the temperature of the latter tube and causes more steam 35 to be generated.

I now prefer to make the drop tubes 20 as well as the fire tubes 55, of copper while the boiler shell and the holding tube 21 may be of steel or other material if desired.

40 Suitable fire tubes 60 are shown as passing through the shell 11. The ends of these tubes 60 may be flanged or upset against the ends of the shell 11.

Having thus described my invention, I 45 claim:

1. In a boiler, a shell having a plurality of water tubes and a plurality of fire tubes extending therethrough, with a set of fire tubes about each water tube, a drop tube 50 extending from each of said water tubes and spaced from one another, said drop tubes having members constituting fire tubes fixedly secured to the exterior surfaces thereof, said first mentioned fire tubes and said second fire tubes having their axes arranged 55 parallel.

2. In a boiler, a shell having a drop tube secured thereto and in communication with the interior thereof, a plurality of flues secured to and spaced about the periphery of the drop tube, a holding tube in said casing coaxially arranged with respect to said drop tube and extending from the top to the bottom of said shell, said holding tube and said 60 drop tube being secured together to consti-

tute a continuous tube and means whereby said continuous tube may be readily removed from said shell.

3. In a boiler, a shell having a drop tube secured thereto and in communication with the interior thereof, a plurality of fire tubes in the shell spaced about said drop tube, a holding tube in the shell coaxially arranged with respect to the drop tube, said holding tube being fixedly united to the drop tube, 70 means to provide a steam tight joint between the drop tube and the boiler shell and a closure member for engaging said holding tube to hold the same in the shell and also to prevent leakage between the shell and the holding tube.

4. In a boiler, a shell having a drop tube secured thereto and in communication with the interior thereof, a holding tube arranged within the shell and having its lower extremity united to the drop tube, means for removably maintaining the holding tube in steam tight engagement with the shell, a plurality of flues secured to the periphery of said drop tube and means in said drop tube to cause a circulation of water therethrough.

5. In a boiler, a shell having a drop tube secured thereto and in communication with the interior thereof, a holding tube aligned with the drop tube, a circulation tube extending from a point above the bottom of said shell to a point adjacent the lower end of said drop tube, a flange on the top of said circulation tube, said holding tube having 100 apertures thereon above and below said flange and an aperture adjacent the bottom of said circulation tube.

6. In a boiler, a shell having a drop tube secured thereto and in communication with the interior thereof, a holding tube in said shell coacting with said drop tube and extending from the top to the bottom of said shell, said holding tube and said drop tube being secured together, to constitute a unitary structure, a circulation tube in said drop tube, a flange on the top of said circulation tube arranged adjacent the interior wall of said holding tube, an aperture adjacent the bottom of said circulation tube, a spring for holding said circulation tube in place, a cap for closing said holding tube, said cap serving to hold the drop tube in the shell, fire tubes passing through the shell and flues arranged upon the drop tube.

7. In a boiler, a shell having a drop tube secured thereto and in communication with the interior thereof, means to hold said drop tube in said shell, a readily removable water circulation tube in said drop tube, and a spring for holding the circulation tube in place in said drop tube.

In testimony whereof, I hereunto affix my signature.

LUCIUS D. COPELAND.
